UNITED STATES PATENT OFFICE.

WILLIS G. BANKS, OF EAST ORANGE, NEW JERSEY.

DESIGN FOR A CAP FOR A CLOTHES POST OR SIMILAR ARTICLE.

60,439.

Specification for Design.

Patented Feb. 21, 1922.

Application filed August 13, 1921. Serial No. 492,166. Term of patent 7 years.

To all whom it may concern:

Be it known that I, WILLIS G. BANKS, a citizen of the United States, residing at East Orange, in the county of Essex and State of New Jersey, have invented a new, original, and ornamental Design for a Cap for Clothes Posts or Similar Articles, of which the following is a specification, reference being had to the accompanying drawing, forming part thereof.

The figure is a perspective view of a cap for a clothes post embodying my design.

I claim:

The ornamental design for a cap for a clothes post or similar article, as shown.

WILLIS G. BANKS.
